UNITED STATES PATENT OFFICE

CHARLES F. JONES, OF LEXINGTON, KENTUCKY

SWITCH STAND

Application filed September 15, 1930. Serial No. 482,049.

This invention relates to a switch stand, and has for its object to provide, in a manner as hereinafter set forth a switch stand having an improved mechanism, which not only insures the positive throwing of the switch points in either direction, but, also, effects a positive lock for the switch points after being thrown to switching position, as well as further a fixed positive setting of the signal, and with the setting of the signal had simultaneously with the throwing of the switch point to switching position.

Further objects of the invention are to provide, in a manner as hereinafter set forth, a switch stand for the purpose referred to which is comparatively simple in its construction and arrangement, strong, compact, positive in its action, thoroughly efficient in its use, conveniently operated for the purpose intended, readily assembled, quickly installed with respect to a track, and comparatively inexpensive to set up.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a plan view showing the adaptation of a switch stand in accordance with this invention with respect to a railroad track.

Figure 2 is an elevation looking towards the outer side of a switch stand in accordance with this invention and with the stand set up with respect to a railway track.

Figure 3 is a top plan view upon an enlarged scale of a switch stand in accordance with this invention with the cover of the housing removed to show a shifting mechanism for the switch point, the signal and also locking means for the switch point when the latter is thrown to switching position.

Figure 4 is an end elevation with the body of the housing in horizontal section.

Figure 5 is a side elevation with the housing in longitudinal section.

Figure 6 is an elevation of the locking element, throwing element and operating lever in position when the switch is in normal position and locked.

Figure 7 is a side elevation of the locking element, throwing element and operating lever showing the position of such parts when the switch is in normal position and unlocked.

Figure 8 is a side elevation of the locking element, throwing element and operating lever showing the position of the parts when the switch is reversed and unlocked.

Figure 9 is a side elevation of the locking element, throwing element and operating lever showing the position of such parts when the switch is reversed and locked.

Figure 10 is a fragmentary view of the locking element and retainer when positioned relatively to each other.

Figure 11 is a fragmentary view in top plan of the locking element and retainer showing one position thereof relatively to each other.

Figure 12 is a fragmentary view in side elevation of the locking element.

The drawing illustrates a main track and a siding or branch track, the former comprising track rail sections 1, 2 and the part 3 of the track rail section 4. The track rail section 1 is shiftable. The siding or branch track comprises an inclined shiftable track rail section 5 and the inclined part 6 of track rail section 4. One end of the section 1 provides a switch point 7 which when it abuts the part 6 of track rail section 4 forms a continuation of the part 3 of section 4. One end of the track rail section 5 provides a switch point 8 which is adapted to coact with the track rail section 2, when switch point 8 is shifted to provide in connection with the part 6 a siding or branch for a train to pass from the siding or branch onto the main track or for passing from the main track onto the siding or branch. The ties or sleepers for the track sections are indicated at 9 and certain of them which are designated 10 are of greater length.

Figure 1 is a plan view showing the adaptation of a switch stand in accordance with this invention with respect to a railroad track.

than the other ties or sleepers 9. The ties or sleepers 10 project a substantial distance from the part 6 of the track rail 4 and support the housing carrying a mechanism for shifting and locking a switch point or tongue and for shifting a signal to the desired position. The switch point 7 is connected to the switch point 8 by a coupling bar 11 which has its ends fixedly secured to the inner faces of said points. The coupling bar 11 provides for the switch points to shift in unison. Projecting from the coupling bar 11 is an apertured extension 12 having one end of the throw rod 13 fixedly connected therewith. The throw rod 13 passes below the part 6 of the rail section 4 and below the rail section 1. A retaining rod 14 is coupled to switch points 7, 8 at the free ends thereof. Angles 15 and holdfast devices 16 are employed for fixedly securing the retaining rod 14 to the switch points 7, 8. The throw rod 13 and retaining rod 14 are disposed transversely with respect to the main track and retaining rod 14 passes below part 3 of rail section 4 and below rail section 2. The throw rod 13 and retaining rod 14 form elements of the switch stand in accordance with this invention.

The switch stand includes a housing comprising an open bottom body portion or cover 17 of the desired height and which seats upon a bottom forming member 18 provided with a rib 19 which is spaced from the edge of member 17. The rib 19 is vertically disposed. The member 18 is of rectangular contour and includes means in the form of spaced laterally extending apertured lugs 20 for the passage of holdfast devices to anchor such member to the sleepers 10 adjacent one side of the railway track. The member 18, centrally at one side thereof, that is, its inner side, is formed with a triangular shaped extension 21. The member 18 centrally thereof is formed with a rectangular opening 22. The rib 19 at each end of member 18 is cut away to provide a groove 23 which will be presently referred to. The bottom of the body portion or cover 17 is formed with an outwardly directed flange 24 which seats upon the upper face of rib 19. The ends of the body portion or cover 17 are formed with cutouts 25 providing openings registering with the groove 23. The purpose of the openings provided by the cutouts and grooves will be presently referred to. Formed integral with the upper face of member 18 between its transverse median and each end is a rectangular projection constituting a guide. The projections are indicated at 26, 27, the former provided with grooves 28, 29 and the latter with grooves 30, 31. The purpose of the grooves 28, 29, 30 and 31 will be presently referred to. Mounted upon the projections 26, 27, as well as being secured therewith are retaining plates 32, 33 respectively. Holdfast devices 34 are employed for securing the plates 32, 33 in position. The

projections 26, 27 are disposed transversely with respect to the member 18 and the grooves 28, 29, 30 and 31 are disposed transversely of the projections. The grooves 28 and 30 are arranged in alignment. The grooves 29 and 31 are arranged in alignment. The grooves 28 and 30 are arranged in alignment with the openings provided by the cutout portions 25 of the body portion or cover 17 of the housing.

Formed integral with the upper face of the member 18, at one side and at the transverse median thereof is a grooved support 35 which in connection with a cap member 36 provides a bearing for the purpose to be presently referred to. The cap member 36 is secured to the support 35 by holdfast devices 37. The cap member is formed with a semi-circular groove and which opposes the semi-circular groove formed at the top of the support 35. The groove in the cap member is designated 38 and that in the support 39. The support 35 and cap member 36 provide a bearing.

Rotatably mounted in the bearing provided by the support 35 and cap member 36 is the operating shaft 41 and the latter projects outwardly and inwardly from the bearing referred to. The shaft 41 is disposed transversely of member 18. Collars 42, 43 and 44 are carried by the shaft 41. The shaft 41 is provided with a pair of crank arms 45, 46 disposed at right angles with respect to each other. The outer end of the arm 45 is formed with a yoke 47 which is offset with respect to such end. The outer end of the arm 46 is provided with a yoke 48 which is offset with respect to such end. The collar 44 is interposed between the inner end of the arm 45 and the support 35 and cap member 36. The collar 43 is interposed between the inner end of the arm 46 and the inner end of the arm 45. The collar 42 is positioned against the inner end of arm 46, and is retained in position by a cotter pin 49. Journaled in the yoke 47 of the arm 45 is a roller 50 and journaled in the yoke 48 of the arm 46 is a roller 51. The purpose of the rollers 50, 51 will be presently referred to. That portion of the shaft 41 which projects beyond the body portion or cover 17 of the housing is squared and extends through the inner end 52 of an operating lever 53. The lever 53 is so connected to shaft 41 whereby the shaft cannot turn relatively to the lever or the lever relatively to the shaft. A securing nut is mounted on the outer end of shaft 41 and such nut is indicated at 55. The outer end of the lever 53 carries a counterweight 54.

The switch stand includes a locking element mounted for shifting in opposite directions lengthwise with respect to the bottom member 18. The locking element comprises a bar 56 standing on its lower longitudinal edge and of rectangular contour in vertical section. The bar 56 is positioned in the

grooves 23, 28 and 30. The bar 56 in proximity to one end thereof is formed with a notch 57 of the desired width and height and which opens at the bottom edge 58 of the bar 56. The bar 56 has as an integral part thereon of a depending U-shaped portion 59 providing a recess 60. Intermediate the ends of the bar 56 it is formed with a cutout having the edges thereof providing continuations of the inner edge of the depending U-shaped part 59. Formed integral with the bar 56 at the top thereof is a skeleton extension or link comprising an inverted U-shaped top part 61 forming a recess 62, a curved side part 63 which extends from one side of the part 61 and terminates in the top of bar 56, and a side part 65 consisting of an incurved upper end portion 66 integral with the other side of part 61, a forwardly extending downwardly inclined intermediate portion 67 and a curved lower portion 68 which merges into the top of the bar 56 and is oppositely curved with respect to the portion 66. The roller 50 is positioned to ride against the inner edge of the skeleton extension or link and also to engage in the recesses 60 and 62 and the purpose therefor will be presently referred to.

The switch stand further includes a throwing element consisting of a bar 69 shorter in length than the bar 56 and standing on its lower longitudinal edge. The bar 69 has a depending U-shaped strap-like part 70 which provides a recess 72. The bar 69 also is formed with a cutout 73' having its edges forming continuations of the inner edge of the part 70. Formed integral with the top edge of bar 69 is an upstanding link 73 which gradually increases in width from its lower to its upper end and has its inner edge formed of continuations of the edges of the cutout 73'. The roller 51 carried by the arm 46 is adapted to ride against the inner edge of link 73 and enter recess 72 and the purpose thereof will be presently referred to. The bar 69 is mounted in the grooves 29, 31. The bar 69 is furthermore provided with a right angularly disposed yoke-shaped lateral extension 74 carrying centrally of its outer end a headed pin or stud 75. The function of the headed pin or stud 75 will be presently referred to.

The part 59 of the locking element and the part 70 of the throwing element depend through the opening 22 in member 18. The opening 22 is of a size to provide the necessary clearance for the shifting of the locking and throwing elements lengthwise of the bottom member 18 when such elements are operated. The locking element is of greater length than the throwing element and the bars of said elements are arranged in parallelism.

Formed integral with the member 18 at the portion 21 thereof, and depending below said member 18 is a vertically disposed sleeve 76

through which extends a vertically disposed shaft 77, the latter rotating on a vertical axis, and providing for the setting of a signal connected thereto, and in connection with a lever arm 79 carried thereby the throwing of a switch point simultaneously with the setting of the signal.

The shaft 77 extends above the body portion or cover 17 of the housing and depends below the sleeve 76. The lever arm 79 is arranged on shaft 77 at the lower end thereof and is provided with a pair of openings 80, 81 at the end thereof. Fixed to the shaft 77 and bearing against the upper end of the sleeve 76 is a crank arm 82 having a bifurcated outer portion 83 for straddling the headed pin or stud 75. The lever arm 79 is adapted to be pivotally connected, as at 84 to the throw rod 12. Only one of the openings of the lever arm 79 is employed, depending on which way it is desired to throw the switch points. The lever arm 79 is connected by the opening 80 and pivot 84 to the yoke-shaped inner end 85 of the throw rod 12. The upper end of the shaft 77 is provided with means, as indicated at 86 for detachably connecting the signal 78 therewith.

The retaining rod 14 in proximity to one end thereof is provided with a pair of spaced notches 87, 88 of the desired depth and width and which open at the top edge of rod 14. The notches 87, 88 associate with the bar 56 of the locking element. The notch 87 in the bar 56 associates with the retaining rod 14. The retaining rod 14 has its outer end supported and guided in a grooved casting 89 which is integral with and projects from one end of the bottom member 18.

The bar 56 not only shifts lengthwise with respect to the bottom member 18, but the bar 69 also shifts in a like direction. The skeleton extension or link which projects upwardly from and is integral with the bar 56 coacts with the arm 46 to provide for the shifting of the locking element of the switch stand. The link or extension 73 which projects upwardly from and is integral with the bar 69 coacts with the arm 46 for the purpose of shifting the throwing element. The locking element coacts with the retaining rod 14 for the purpose of locking the switch points in position after they have been shifted. The throwing element coacts with the shaft 77 and lever arm 79 for the purpose of throwing the switch points and shifting the signal to the desired position. The shifting of the signal is had simultaneously with the throwing or shifting of the switch points.

It will be assumed that the switch is normal and locked and when in such position provides for trains to travel over the route provided by the switch point 7 on the track rail section 2. The retaining rod cannot slide in the casting 89 because it is prevented from so doing as one end of the bar 56 is extended

through notch 87 of lock rod 14. When lock rod 14 is arranged relatively to the locking element in the manner just referred to switch points 7 and 8 are in locked position. When the lock rod 14 is in the position just referred to the lever 53, locking element and throwing element are in a position as shown in Figure 6. It will be assumed that the lever 53 is thrown from the position shown in Figure 6 to the position shown in Figure 7. As the lever 53 moves into the position shown in Figure 6 the crank arm 45 moves the locking element in the direction of the arrow shown in Figure 7, the roller 50 slips out of cavity 62 and the roller 51 of the crank arm 46 rides along the inner surface of link 73, but up to this time the throwing element has not been moved. The roller 50 slips from cavity 62 and the locking element moves just enough to cause notch 57 to be in such position to allow the retaining rod 14 to pass through such notch. On a continuous shift of lever 53, crank arm 45 will cause roller 50 to ride downwardly against part 63 of the extension or link of the locking element, without moving the latter, but the crank arm 46 will cause roller 51 to rotate in cavity 72 of the throwing element for moving the latter in the direction of the arrow shown in Figure 8. When the throwing element moves in the direction of the arrow in Figure 8 the stud 75 on the lateral extension 74 will slide in the bifurcated end of crank arm 82 thereby turning shaft 77. When shaft 77 turns, the lever arm 79 will be carried therewith and the switch points 7, 8 will be shifted from the position shown in Figure 1 to a position whereby the switch point 8 will abut the track rail section 2 thereby providing for a train to travel along the main track onto the branch or siding or from the branch or siding onto the main track. When the shaft 77 is turned it will also provide for the shifting of the signal or target 78. The switch is now reversed but not locked, however, the retaining rod 14 is moved over so that its notch 88 is directly in line with the end of bar 56. Now lever 53 is turned downward until it takes the position shown in Figure 9 and the roller 51 will ride against link 73, but will not shift the throwing element, but the roller 50 is now located in the recess of cavity 60 and moves the locking element in the direction shown by the arrow in Figure 9, so that notch 57 is not located to allow movement of the retaining rod 14, thus the switch is now locked in a reversed position.

The locking element, in connection with the crank arm 45 provides means for locking the switch in a position to which it has been fixed.

It is thought that the many advantages of a switch stand, in accordance with this invention and for the purpose set forth can be readily understood, and although the pre-

ferred embodiments of the invention is as illustrated and described, yet it is to be understood that changes in the details of construction can be had which fall within the scope of the invention as claimed. 70

What I claim is:

1. A switch stand for throwing the switch points of a pair alternately to active position and for locking said points simultaneously in set position comprising the combination of a shiftable retaining rod for, common to and adapted to be secured to the switch points, a shiftable throw rod for, common to and adapted to be connected to the switch points, a shiftable locking element coacting with said retaining rod for locking the switch points in set position, a shiftable throwing element and disposed parallel to said locking element, a rotatable shaft provided with a pair of crank arms angularly disposed to each other, one of said arms coacting with and engaging in said locking element and the other coacting with and engaging in said throwing element for shifting said elements successively in opposite directions and with the locking element being shifted in advance of the shift of the throwing element, and means operated from said throwing element for shifting said throw rod to move the switch points to set position and for setting a signal. 95

2. A switch stand for throwing the switch points of a pair alternately to active position and for locking said points simultaneously in set position comprising the combination of a shiftable retaining rod for, common to and adapted to be secured to the switch points, a shiftable throw rod for, common to and adapted to be connected to the switch points, a shiftable locking element coacting with said retaining rod for locking the switch points in set position, a shiftable throwing element, a rotatable shaft provided with a pair of crank arms angularly disposed to each other, one of said arms coacting with said locking element and the other coacting with said throwing element for shifting said elements, means operated from said throwing element for shifting said throw rod to move the switch points to set position and for setting a signal, each of said arms provided with a roller, and each of said elements having parts against which travels a roller, and said locking element having spaced means to alternately receive the roller of the crank arm coacting with such element to lock the latter 110 from shifting. 115

3. A switch stand for throwing the switch points of a pair alternately to active position, for locking said points simultaneously in set position and for setting a signal when a switch point is shifted to active position comprising the combination of a shifting means for the switch points, said means including a rotatable, vertically disposed shaft adapted to have secured to its upper end a 130

signal to bodily move therewith, a retainer for maintaining the switch points in set position, a longitudinally shiftable throwing element operatively connected with said shifting means for rotating said shaft, a longitudinally shiftable locking element disposed parallel to said throwing element and coacting with said retainer for locking the switch points in set position, and a rotatable element having means common to and engaging in said elements for shifting them successively longitudinally in opposite directions to provide for the moving of the switch points to and for locking them in set position and with the locking element being shifted in advance of the shift of the throwing element.

4. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element disposed parallel to the throwing element and inter-engaging with said retainer for locking the switch points in set position, and a rotatable shaft extending through said throwing and locking elements and provided with a pair of crank arms disposed at an angle to each other and slidably engaging with said locking and throwing elements for longitudinally shifting them, and said locking element including spaced means for receiving the outer end of that crank arm associated therewith for holding said locking element in locking position relative to said retainer.

35

5. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element disposed parallel to the throwing element and inter-engaging with said retainer for locking the switch points in set position, and a rotatable shaft extending through said throwing and locking elements and provided with a pair of crank arms disposed at an angle to each other and slidably engaging with said locking and throwing elements for longitudinally shifting them successively in opposite directions and with the shift of the locking element being in advance of the shift of the throwing element.

45

6. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element disposed parallel to the throwing element and inter-engaging with said retainer for locking the switch points in set position, and a rotatable shaft extending through said throwing and locking elements and provided with a pair of crank arms disposed at an angle to each other and slidably engaging with said locking and throwing elements for longitudinally shifting them successively in opposite directions and with the shift of the locking element being in advance of the shift of the throwing element.

55

7. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element disposed parallel to the throwing element and inter-engaging with said retainer for locking the switch points in set position, and a rotatable shaft extending through said throwing and locking elements and provided with a pair of crank arms disposed at an angle to each other and slidably engaging with said locking and throwing elements for longitudinally shifting them successively in opposite directions and with the shift of the locking element being in advance of the shift of the throwing element.

80

8. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element inter-engaging with said retainer for locking the switch points in set position, a rotatable shaft extending through said throwing and locking elements and provided with a pair of crank arms disposed at an angle to each other and slidably engaging with said locking and throwing elements for longitudinally shifting them, and said locking element including spaced means for receiving the outer end of that crank arm associated therewith for holding said locking element in locking position relative to said retainer.

90

9. In a switch stand for throwing the switch points of a pair alternately to active position and for simultaneously locking one of said points in active and the other in inactive position, means for simultaneously shifting the switch points, a retainer for, common to and bodily shiftable with the switch points, a longitudinally shiftable throwing element operatively connected with and operating said means, a longitudinally shiftable locking element disposed parallel to said throwing element and inter-engaging with said retainer for locking it to retain the switch points in the position set, and rotatable means extending through said elements and including crank arms riding against said elements for longitudinally shifting them successively in opposite directions for setting and locking the switch points in set position and with the shift of the locking being in advance of the shift of the throwing element.

100

10. In a switch stand a locking element for a retainer for a pair of switch points, said element including a longitudinally shiftable bar standing on its lower longitudinal edge and cutout intermediate its ends, an extension depending from said edge, providing a cavity and having its inner edge forming a continuation of the edges of such cutout, and an upstanding, irregular shaped link integral with the top edge of the said bar and having its inner edge forming a continuation of the edges of such cutout, said link having a cavity at its upper end.

9. In a switch stand a throwing element for operating the shifting mechanism for a pair of switch points, said element including a longitudinally shiftable bar standing on its lower longitudinal edge and cutout intermediate its ends, an extension depending from said edge, providing a cavity and having its inner edge forming a continuation of the edges of such cutout, an upstanding link integral at its lower end with the top edge of said bar and having its inner edge forming a continuation of the edges of said cutout, a laterally extending yoke projecting from one side of said bar, and a headed stud carried by said yoke and adapted to slidably engage with said mechanism for operating the latter.

10. In a switch stand a throwing element for operating the shifting mechanism for a pair of switch points, said element including a longitudinally shiftable bar standing on its lower longitudinal edge and cutout intermediate its ends, an extension depending from said edge, providing a cavity and having its inner edge forming a continuation of the edges of such cutout, an upstanding link integral at its lower end with the top edge of said bar and having its inner edge forming a continuation of the edges of said cutout, a laterally extending yoke projecting from one side of said bar, a headed stud carried by said yoke and adapted to slidably engage with said mechanism for operating the latter, said link gradually increasing in width from its lower end.

11. A switch stand for throwing the switch points of a pair alternately to active position and for locking said points simultaneously in set position comprising the combination of a shiftable retaining rod for, common to and adapted to be secured to the switch points, a shiftable throw rod for, common to and adapted to be connected to the switch points, a shiftable locking element coacting with said retaining rod for locking the switch points in set position, a shiftable throwing element, a rotatable shaft provided with a pair of crank arms angularly disposed to each other, one of said arms coacting with said locking element and the other coacting with said throwing element for shifting said elements, means operated from said throwing element for shifting said throw rod to move the switch points to set position and for setting a signal, guiding means for said locking and throwing elements, and said locking and throwing elements being disposed in parallel spaced relation.

12. A switch stand for throwing the switch points of a pair alternately to active position, for locking said points simultaneously in set position and for setting a signal when a switch point is shifted to active position comprising the combination of a shifting means for the switch points, said means including a rotatable, vertically disposed shaft adapted

to have secured to its upper end a signal to bodily move therewith, a retainer for maintaining the switch points in set position, a longitudinally shiftable throwing element operatively connected with said shifting means for rotating said shaft, a longitudinally shiftable locking element coacting with said retainer for locking the switch points in set position, a rotatable element having means common to and engaging in said elements for shifting them longitudinally to provide for the moving of the switch points to and for locking them in set position, guiding means for said locking and throwing elements, and said locking and throwing elements being disposed in parallel spaced relation.

13. In a switch stand for throwing the switch points of a pair alternately to active position, for locking a switch point of the pair in active position and for setting a signal or target simultaneously with the shifting of the switch point to active position, a rotatable element for simultaneously shifting the signal and a switch point throw rod, a retainer for and adapted to be connected to and bodily moving with the switch points, a longitudinally shifting throwing element operatively connected with said rotatable element for operating the latter, a longitudinally shiftable locking element inter-engaging with said retainer for locking the switch points in set position, and a rotatable shaft extending through said throwing and locking elements and provided with a pair of crank arms disposed at an angle to each other and slidably engaging with said locking and throwing elements for longitudinally shifting them, guiding means for said locking and throwing elements, and said locking and throwing elements being disposed in parallel spaced relation.

14. In a switch stand for throwing the switch points of a pair alternately to active position and for simultaneously locking one of said points in active and the other in inactive position, means for simultaneously shifting the switch points, a retainer for, common to and bodily shiftable with the switch points, a longitudinally shiftable throwing element operatively connected with and operating said means, a longitudinally shiftable locking element inter-engaging with said retainer for locking it to retain the switch points in the position set, and rotatable means extending through said elements and including crank arms riding against said elements for longitudinally shifting them successively in opposite directions for setting or locking the switch points in set position and with the shift of the locking element being in advance of the shift of the throwing element.

15. A switch stand for throwing the switch points of a pair alternately to active position and for locking said points simultaneously in set position comprising the combination of a

shiftable retaining rod for, common to and adapted to be secured to the switch points, a shiftable throw rod for, common to and adapted to be connected to the switch 5 points, a shiftable locking element coacting with said retaining rod for locking the switch points in set position, a shiftable throwing element, a rotatable shaft provided with a pair of crank arms angularly disposed to each 10 other, one of said arms coacting with said locking element and the other coacting with said throwing element for shifting said elements, means operated from said throwing element for shifting said throw rod to move 15 the switch points to set position and for setting a signal, guiding means for said locking and throwing elements, said locking and throwing elements being disposed in parallel spaced relation, and said locking element being 20 of greater length than said throwing element.

16. In a switch stand for throwing the switch points of a pair alternately to active position and for simultaneously locking one 25 of said points in active and the other in inactive position, means for simultaneously shifting the switch points, a retainer for, common to and bodily shiftable with the switch points, a longitudinally shiftable throwing 30 element operatively connected with and operating said means, a longitudinally shiftable locking element inter-engaging with said retainer for locking it to retain the switch points in the position set, rotatable means extending through said elements and including crank arms riding against said elements for longitudinally shifting them for setting or locking the switch points in set position, and said locking element being of greater length 35 than said throwing element.

17. A switch stand for throwing the switch points of a pair alternately to active position and for locking said points simultaneously in set position comprising the combination of a shiftable retaining rod for, common to and adapted to be secured to the switch points, a shiftable throw rod for, common to and adapted to be connected to the switch points, a shiftable locking element coacting with said retaining rod for locking the switch points in set position, a shiftable throwing element, a rotatable shaft provided with a pair of crank arms angularly disposed to each other, one of said arms coacting with said locking element and the other coacting with said throwing element for shifting said elements, means operated from said throwing element for shifting said throw rod to move the switch points to set position and for setting a signal, and a combined support and guide for said retaining rod, said locking element being notched in proximity to one end for the passage of the retaining rod, and said retaining rod provided with a pair of spaced 65

notches to selectively receive said locking element.

18. In a switch stand for throwing the switch points of a pair alternately to active position and for simultaneously locking one of said points in active and the other in inactive position, means for simultaneously shifting the switch points, a retainer for, common to and bodily shiftable with the switch points, a longitudinally shiftable throwing element operatively connected with and operating said means, a longitudinally shiftable locking element inter-engaging with said retainer for locking it to retain the switch points in the position set, rotatable means extending through said elements and including crank arms riding against said elements for longitudinally shifting them for setting or locking the switch points in set position, a combined guide and support for said retainer, said locking element having a notch in proximity to one end for the passage of the retainer, and said retainer having a pair of spaced notches to selectively receive said locking element.

In testimony whereof, I affix my signature 90 hereto.

CHARLES F. JONES.
